UNITED STATES PATENT OFFICE.

JACOB GOLDMAN, OF BALTIMORE, MARYLAND.

OVERCOAT.

1,100,871.

Specification of Letters Patent. Patented June 23, 1914.

Application filed March 5, 1913. Serial No. 732,153.

To all whom it may concern:

Be it known that I, JACOB GOLDMAN, a citizen of the United States, residing at Baltimore, State of Maryland, have invented a new and useful Overcoat, of which the following is a specification.

The device forming the subject matter of this application is a coat adapted to combine the features of a rain coat and a common top coat.

The invention aims to provide novel means for holding the inner and outer coats together, to provide novel means whereby portions of the inner coat may be manipulated and adjusted, and to improve generally, devices of that type to which the present invention appertains.

With the above and other objects in view which will appear as the description proceeds, the invention resides in the combination and arrangement of parts and in the details of construction hereinafter described and claimed, it being understood that changes in the precise embodiment of invention herein disclosed can be made within the scope of what is claimed without departing from the spirit of the invention.

In the drawings:—Figure 1 shows the invention in perspective, parts being broken away, the top coat being disposed outermost; Fig. 2 is a perspective view showing the top or outer coat located upon the inside of the garment; Fig. 3 is a fragmental perspective of the inner or rain coat; Fig. 4 is a transverse section showing the edge of the rain coat folded back and retained; Fig. 5 is a transverse section showing the edge of the rain coat extended; Fig. 6 is a sectional detail showing the sleeve of the rain coat retracted; Fig. 7 is a fragmental section showing the sleeve of the rain coat advanced; and Fig. 8 is a perspective of the garment as the same will appear when the rain coat is outwardly disposed.

In carrying out the invention there is provided an outer coat 1 and an inner coat 2 located within the outer coat 1. The outer coat 1 is fashioned from any suitable material and the inner coat 2 is fashioned from rain proof material. The coats 1 and 2 are held together by socket and stud fasteners 3 or like means, located upon the front of the coat as will be understood best when Fig. 4 is examined. The arms 5 of the inner coat 2 lie within the arms 4 of the outer coat 1.

The lower end of each arm 5 of the inner coat 2 is turned up to form a cuff 6. The cuff 6 is maintained in upturned relation, and above the lower end of the sleeve 4 by means of a snap and stud fastener 7 shown in Fig. 1, one member of the snap and stud fastener 7 being located on the inside of the sleeve 5 and the other member of the fastener being located on the inside of the cuff 6. The cuff 6 may thus be upheld as shown in Fig. 6, so that the sleeve 4 of the outer coat 1 will protrude beyond the cuff 6 when the coat 1 is disposed upon the outside of the garment. When, however, the inner or rain coat forms the exterior of the garment, the cuff 6 may be lowered, as shown in Fig. 7, so as to protect the lower end of the sleeve 4.

The outer coat 1 is held together by means of buttons 8 adapted to engage button holes 9, the buttons 8 being located on the outside of the coat 1, presupposing that the same forms the exterior of the garment. The inner coat 2 is held together by means of buttons 10 adapted to engage button holes 11. The buttons 10 are located on the inside of the inner coat 2 presupposing that the inner coat 2 constitutes the interior of the garment.

The inner coat 2 is folded transversely to form longitudinally extended tongues 12. The edge 14 of the inner coat 2 is adapted to be turned back as indicated at 15 and to be disposed beneath the tongue 12. The tongue 12 is provided with a socket 17 and the edge 15 of the coat 2 is provided with a stud 16 which is adapted to be received in the socket.

The inner coat 2 is split as indicated at 18, along the line of union between the lapel 19 and the collar 20 to cause the end of the collar to form a free tongue. A removable strip 21 extends across the split 18 and is held in place by fasteners 22. Upon its inner face, the outer coat 1 is provided with a button 23.

Presupposing that the outer coat 1 forms the exterior of the garment, the edges of the coat 1 are united by means of the buttons 8 and the button holes 9. The strip 21 is loosened by detaching the fasteners 22 and thus, the edges of the split 18 are left free. By this operation, the lapel 19 and the collar 20 of the inner coat 2 may be folded back, so as to lie beneath the corresponding

parts of the outer coat 1. Under the circumstances above pointed out, the cuff 6 of the inner coat is drawn upwardly as shown in Fig. 6 and is engaged by the fasteners 7 which are shown in Fig. 1.

When it is desired to employ the garment as a rain coat, the garment is turned inside out. Under such circumstances, the button 23 lies upon the outside of the outer coat 1 and may be assembled with the uppermost button hole 9 to hold the outer coat; (which has now become the inner coat) in place adjacent the top. The free edges 15 of the inner coat 2 are disengaged from the tongues 12 by detaching the fastening elements 16 and 17 from each other, whereupon the free edge of the inner coat 2 will protrude beyond the free edge of the coat 1, as clearly shown in Fig. 5. The free edges 15 of the coat 2 may then be united through the medium of the buttons 10 and the button holes 11.

When the coat 2 is disposed inwardly, that is when the garment is used as an ordinary over coat, the edges of the inner coat 2 are turned back as shown in Fig. 4, and are engaged with the tongues 12.

The coats 1 and 2 may be separated readily, by detaching the fasteners 3. It is to be observed that the collar 20 is separated from the lapel 19 by a notch, as clearly shown in Fig. 1 of the drawings. The split 18 extends circumferentially of the garment and rearwardly from the apex of the notch, along the line of union between the collar 20 and the inner coat proper, to form a free tongue at the inner end of the collar. When the lapel and the collar of the inner coat are folded beneath the outer coat, the free tongue is adapted to overlie the lapel and thus a bulging is prevented.

Having thus described the invention, what is claimed is:—

1. A garment comprising an inner coat and an outer coat, the inner coat having a 45 collar and a lapel separated by a notch, the inner coat being split upwardly and rearwardly from the apex of the notch, and at an angle to the notch, and along the line of union between the collar and the inner 50 coat proper to form a free tongue at the end of the collar, the tongue being adapted to overlie the lapel and prevent bulging when the lapel and the collar of the inner coat are turned beneath the outer coat; and a 55 strip detachably secured across the split.

2. A garment comprising an inner coat and an outer coat, the inner coat being folded upon itself to form a longitudinally extended tongue and being prolonged beyond the tongue to form a free edge, the free edge of the inner coat being folded upon itself to lie beneath the tongue, the said free edge of the inner coat and the tongue having interengaging elements, the edge of the outer coat protruding beyond the said edge of the inner coat when the latter is folded and when the interengaging elements are connected, and the said edge of the inner coat protruding beyond the edge of the outer coat when the said edge of the inner coat is unfolded and straightened out; means for uniting the free edges of the inner coat; and means for uniting the free edges of the outer coat. 75

In testimony that I claim the foregoing as my own, I have hereto affixed my signature in the presence of two witnesses.

JACOB GOLDMAN.
